DESIGN FOR SLACKS

Frank I. Frankel, New York, N. Y.

Application March 10, 1942, Serial No. 106,133

Term of patent 7 years

To all whom it may concern:

Be it known that I, Frank I. Frankel, a citizen of the United States of America, residing in New York city, county of New York, and State of New York, have invented a new, original, and ornamental Design for Slacks, of which the following is a specification, reference being had to the accompanying drawing, forming part thereof, wherein,

Figure 1 is a front view of a pair of slacks showing my new design, and

Figure 2 is a rear view of the slacks shown in Fig. 1.

The characteristic feature of my design resides in the combination on the specific slacks disclosed of the specific pocket members and arrangement thereof, all as shown.

I claim:

The ornamental design for slacks, substantially as shown and described.

FRANK I. FRANKEL.
